(57) **CLAIM**

The ornamental design for a carrier bag, as shown and described.

DESCRIPTION

1. Carrier bag
- 1.1 : Perspective
- 1.2 : Front
- 1.3 : Back
- 1.4 : Right
- 1.5 : Left
- 1.6 : Top
- 1.7 : Bottom

The carrier bag comprises a body that is open towards the top and has two ribbon handles; the ends of the handles are connected externally to the edge of the opening in the body and extend obliquely to the longitudinal direction of the handles; the ends of the bag body have a pattern consisting of a vertical strip and a triangle at the base, said triangle being connected to the lower end of the strip; the figures show, in sequence, the carrier bag in perspective view, front view, rear view, right-hand view, left-hand view, top view and bottom view.
